UNITED STATES PATENT OFFICE.

DENNIS DILLON AND HUGH J. WELSH, OF PITTSBURG, PENNSYLVANIA

CONDIMENT-HOLDER.

No. 925,464.

Specification of Letters Patent. Patented June 22, 1909.

Application filed September 8, 1908. Serial No. 451,930.

To all whom it may concern:

Be it known that we, DENNIS DILLON and HUGH J. WELSH, citizens of the United States, residents of Pittsburg, in the county 5 of Allegheny and State of Pennsylvania, have invented a new and useful Improvement in Condiment-Holders; and we do hereby declare the following to be a full, clear, and exact description thereof.

10 The invention pertains to a condiment holder, and particularly to a holder adapted to contain separately, more than one species of condiments.

15 The object of our invention is to provide a novel and convenient holder wherein different condiments may be contained in separate compartments, from either of which the contents thereof may be shaken while the contents of another compartment is securely 20 retained therein. And a further object of our invention is to provide a holder wherein the opening of one compartment and the closing of another can be effected by a single movement.

25 In the accompanying drawings, Figure 1 is a view in elevation, of a holder having our invention connected thereto. Fig. 2 is a sectional view on lines 2—2 of Fig. 1. Fig. 3 is a plan view without a cap.

30 The reference numerals in the following specification refer to similar parts in the drawings, in which is a holder 5 having a partition 6 adapted to fit the inner diameter of the holder 5, its narrow sides being formed 35 to suit the inner contour thereof to form the compartments 7 and 8. In the upper end of the holder are perforations 9, 10, each of which communicates with a different compartment of the holder, and above the perforations is a cap 11 adapted to be slidably attached to the open end 12 of the holder to close the same. Operatively secured to the upper portion of the partition 6 is a small lever 13 which is suitably connected at each

40 end thereof to one end of the links 14 and 15, the other end of said links being attached to the slidable parts 16 and 17 which are secured to the small studs 18 and 19 slidably fitted in the grooves 20.

With the parts constructed as shown and described, and the compartments supplied with condiments and cap 11 covering the otherwise open end of the holder, the operation of our invention is as follows: By moving the stud 18 from its lower position in the 55 grooves 20 the part 16 is thereby carried upward to close the perforations 9 which movement carries the link 14 upward to reverse the lever 13 and thereby simultaneously forces the part 17 downward from over the 60 perforations 10 from which the contents may then be shaken while the opposite compartment is securely closed. A similar movement of the stud 19 will reverse the relation of those parts. 65

While we have shown and described a particular construction for the mechanical and simultaneous opening of one compartment while closing the other, or vice versa, yet we do not wish to be limited to the exact construction shown, as various modifications may be made therein without departing from the principle of the invention or sacrificing any of its advantages. 70

What we claim as our invention is: 75

In a condiment holder, a partition forming compartments therein, perforations on the exterior sides of the compartments, slots adjacent to the perforations, studs arranged operatively in the slots, slides connected to 80 the end of the studs and held frictionally in position thereby against the sides of the compartments, links connected to the lever and to the slides and adapted to operate said lever by the movement of the studs and the 85 slides, the studs maintaining the adjusted position of the parts by holding the slides frictionally bound against the sides of the compartments.

In testimony whereof, we the said DENNIS 90 DILLON and HUGH J. WELSH have hereunto set our hands.

DENNIS DILLON.
HUGH J. WELSH.
